UNITED STATES PATENT OFFICE

EARL R. JONES, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

CURRENT COLLECTOR FOR HOISTING APPARATUS

Application filed December 28, 1928. Serial No. 329,040.

My invention relates to current collectors, and it has for one object the provision of a simple, efficient and compact current collector particularly applicable to hoisting apparatus.

5 Another object of my invention is to provide a current collector of minimum weight and maximum strength, wherein the several parts are formed of metal stampings.

10 A further object of my invention is to provide a current collector having maximum flexibility both vertical as well as lateral, whereby good contact may be automatically maintained with a supply conductor, regardless of irregularities therein.

15 A still further object of my invention is to provide a current collector adapted to co-act with a conductor, comprising contact means, and means permitting a maximum adjustment in the position of said contact means, so that the proper positioning of said contact means relative to the conductor may be effective at a minimum expenditure of time and effort.

20 25 A still further object of my invention is to provide a current collector for a device, comprising contact means adapted to co-act with a conductor, and means whereby the position of the contact means may be manually adjusted at a plurality of points so as to afford both coarse and fine adjustments.

With these and other objects and applications in mind, my invention further consists in the details of construction and operation 30 and arrangement, hereinafter described and claimed and illustrated in the accompanying drawings, wherein

35 Fig. 1 is a side elevational view of my invention, showing the application thereof to a hoist;

40 Fig. 2 is a detail view of the current collector illustrated in Fig. 1, but showing the position of the adjustable parts when the supply conductor is lowered;

45 Fig. 3 is an end elevational view, partially in section on the line 3—3 of Fig. 1;

50 Fig. 4 is an enlarged detail side elevational view of the collector wheel and its adjacent supporting parts; and

55 Figs. 5 and 6 are sectional views taken on

the lines 5—5 and 6—6 respectively of Fig. 4.

In order to illustrate better the features of my invention, I have shown the same in connection with a hoist of the character set forth in the co-pending application of Hummel and 55 Jones, Serial No. 329,058 filed December 28, 1928, and assigned to the American Engineering Company, though, of course, my invention is capable of other applications. The hoist therein shown comprises broadly 60 pressed-steel trolley frame 1 carrying pairs of wheels 2 and 3 which are mounted on a track formed by an I-beam 4; a pressed-steel hoist body portion 5 which is swingingly mounted on the trolley frame 1 by means of a 65 pivot bolt 6; and a pair of pressed-steel current collectors 7 and 8 for co-action with conductors 9 and 11, respectively, the collectors being adjustably mounted on end portions 12 and 13 of the supporting bolt 6 extending 70 beyond the trolley frame 1.

Heretofore, much difficulty has been experienced in maintaining good contact conditions with the conductors associated with the hoisting apparatus, due to the presence of irregularities in the conductors which are both horizontal and vertical. Difficulty has also been encountered in easily and quickly effecting a desired vertical and lateral adjustment of the current collector with respect to its 75 co-acting conductor. These undesirable results, as well as others noted above, are overcome in my invention by the provision of the current collectors 7 and 8. Since these collectors are identical in all respects, the current 80 collector 7 only will be described in detail. 85

As shown in the drawing, the collector 7 broadly comprises contact means 14, which may take the form of a pressed-steel trolley wheel or shoe having a groove 15 adapted to 90 co-act with the supply conductor 9; a pressed steel yoke or saddle 16 for directly supporting the trolley wheel 14; an insulating member 17 for mounting the yoke 16 on an upper free end 18 of a spiral spring 19, formed of a pressed-steel strip and an adjustable 95 pressed or forged steel supporting bracket 21 having an upper horizontal arm portion 22 formed to provide an adjustable mounting for a clamping portion 23 of the spiral spring 100

19, and also having a transversely extending arm portion 24 adapted to be mounted on the outer end portion 12 of the pivot bolt 6 and clamped in position against the bracket 21 by means of a nut 25.

5 Referring to the yoke 16, of which Figs. 4, 5 and 6 are detail views, a main body portion 26 thereof is provided with a bottom wall 27, and side walls 28 and 29 forming a recess adapted to receive a body portion 32 of the insulating block 17. The portion 32 may be secured in position by means of a bolt 33 which passes through the wall 27, the body portion 32 and a cap 34 which fits 10 over an outer side 35 of the body portion 32 and overlaps adjacent edge portions of the side walls 28 and 29. A projecting end portion 36 of the bolt 33 is threaded for the reception of a clamping nut 37. A second nut 20 38 may be mounted on the threaded end portion 36, in order that a conductor may be suitably attached to the live portion of the current collector 7.

The side walls 28 and 29 of the yoke 16 are 25 provided with outwardly-extending projections 39 and 41, the ends of which are apertured to receive a pin 42 affording the collector wheel 14 a suitable mounting. As illustrated in Fig. 5, an end portion 43 of a 30 hub 44 of the trolley wheel 14 is resiliently held in abutting engagement with an inner side 45 of the yoke extension 41 by means of a spring 46 which engages an opposite end portion 47 of the hub 44. The spring 46 is 35 secured to an inner side of the yoke extension 39. The frictional spring 46 serves to assure good contact relations between the trolley wheel 14 and the yoke 16, so that current may pass readily from the conductor 9 40 to the terminal connection provided by the bolt 33 and nuts 37, 38.

The body portion 32 of the insulating member 17 has imbedded therein a flattened tube 48. The tube 48 projects from the members 45 17 through a recess 49 in an end portion 51 thereof and terminates in an end portion 52 which is positioned slightly beyond an edge 53 of the end portion 51. The flattened tube 48 forms a recess adapted to receive the upper 50 end 18 of the spiral spring 19. These parts may be detachably connected together by means of a clamping bolt 54 and a nut 55. Leakage from the yoke 16 to the spiral spring 19 is prevented by outwardly flaring the end 55 portion 51 of the insulating member 17, as shown in Figs. 4 and 5. Thus, the spiral spring 19 affords a support for the trolley wheel 14 and the yoke 16 and is effectively insulated therefrom.

60 An inner end of the spiral spring 19 is provided with the mounting portion 23 which is formed by bending the end of the spring 19 around the horizontal portion 22 of the adjustable bracket 21, and securing a projecting portion 56 to an adjacent portion 57 of the

spring 19 by means of a bolt and nut 58 and 59. A relatively small or fine vertical adjustment of the trolley wheel 14 relative to the conductor 9 may, therefore, be made by loosening the clamping means 58, 59 and angularly turning the spring 19 about the horizontal portion 22 of the bracket 21 as an axis. 70

In order to minimize the tendency for the mounting means 23 to slip or turn on the horizontal arm 22 of the bracket 21, and in order to assure a uniform angular adjustment of the position of the trolley wheel 14, the arm 22 of the bracket 21 is provided with a plurality of flat sides 61 which extend the length 80 thereof. For purposes of illustration, the arm 22 may be provided with six sides and thus define a supporting member of polygonal cross-section. The mounting portion 23 is similarly formed with a plurality of flat sides 62 which are complementary to the flat sides 61 of the arm 22, as shown in the drawing. Should it be desirable to adjust 85 manually the trolley wheel 14 laterally of the supply conductor 9, this may be readily done by loosening the clamping means 58, 59 and shifting the mounting portion 23 of the spring 19 in the proper direction on the horizontal arm 22 of the bracket 21. 90

As noted above, one of the features of my invention is the automatic adjustment of the trolley wheel 14 that occurs for both vertical and lateral irregularities in the supply conductor 9. This desired result follows from the use of the flat spiral spring 19. By reason 95 of the relatively large flexibility of the spring 19, the trolley wheel 14 automatically accommodates itself to the lateral and vertical irregularities in the conductor 9. Another feature of the spiral spring 19 is that it prevents the collector from assuming a position 100 preventing the return of the trolley wheel 14 into engagement with the conductor 9 when the hoist has been moved beyond the end of the conductor 9. 110

In accordance with my invention, coarse adjustment of the current collector 7 is effected by loosening the nut 25 and manually adjusting the current collector 7 as a whole above the end portion 12 of the pivot bolt 6. Figs. 1 and 2 show the collector bracket 21 in different angular positions. When the desired rough adjustment has been made, the nut 25 is turned so as to clamp at least 115 a base portion 63 of the arm 24 in engagement with the trolley frame 1, as shown, for example, in Fig. 3. 120

Assuming, for example, that it is desired 125 to adjust the current collector 7 from the position shown in Fig. 2 to that shown in Fig. 1, a coarse adjustment is first effected by loosening the nut 25 and then angularly turning the bracket 21 in such direction as to raise vertically the current collector 7 as a whole until the trolley wheel 14 is approxi- 130

mately in the desired elevated position, whereupon the nut 25 is turned to clamp the arm 24 of the bracket 21 against the trolley structure 1. Should the trolley wheel 14 be positioned laterally to the right or the left of the conductor 9, the clamping means 58, 59 is released and the spring 19 is moved on the horizontal arm 22 until the wheel 14 is in proper alignment with the conductor 9. A 10 relatively fine adjustment of the collector 7 is now made in order to assure just the desired frictional engagement between the trolley wheel 14 and the conductor 9 by angularly adjusting the spring 19 on the arm 22. When 15 the trolley wheel 14 has been adjusted to the desired extent, the clamping means 58, 59 is tightened. Should the hoisting apparatus be now moved along the I-beam 4, by reason of the lateral as well as the vertical flexibility 20 of the spring 19, good contact conditions are maintained with the conductors 9 and 11 despite such vertical and lateral irregularities as may occur therein.

While I have shown only one form of embodiment of my invention, for the purpose of describing the same and illustrating its principles of construction and operation, it is apparent that various changes and modifications may be made therein, without departing from the spirit of my invention. I desire, therefore, that only such limitations shall be imposed thereon, as are indicated in the appended claims or as are demanded by the prior art.

35 I claim:

1. A current collector comprising contact means adapted to co-act with a conductor, and supporting means for said contact means including an adjustably-mounted member, 40 and a spring, said spring being mounted for angular as well as lateral adjustment on said member, whereby said contact means may be independently adjusted in a plurality of planes relative to said conductor.

45 2. A current collector comprising contact means adapted to co-act with a conductor, supporting means for said contact means including an adjustably-mounted member, a spring adjustably mounted on said member, and means for insulatingly mounting 50 said contact means on said spring.

55 3. A current collector for a hoist comprising contact means, an angularly-adjustable spiral spring, and means whereby said contact means may be insulatingly mounted on said spiral spring.

60 4. A current collector comprising contact means, an angularly-adjustable member, a spiral spring mounted for angular as well as lateral adjustment on said member, a yoke for supporting said contact means, and means whereby said yoke may be insulatingly mounted on said spring.

65 5. A current collector comprising contact means adapted to co-act with a longitudinal-

ly-extending conductor, a transversely-extending member of polygonal cross section mounted for angular adjustment, and a spiral spring mounted for angular as well as lateral adjustment on said member, said spring being adapted to support said contact means.
